UNITED STATES PATENT OFFICE.

WILLIAM J. ELSOM, OF CORTLAND, NEW YORK, ASSIGNOR TO GEORGE H.
GARRISON AND CHARLES M. DE VANY, OF CORTLAND, NEW YORK.

FERTILIZER-DISTRIBUTER.

No. 836,375.

Specification of Letters Patent.

Patented Nov. 20, 1906.

Application filed February 7, 1906. Serial No. 299,868.

To all whom it may concern:

Be it known that I, WILLIAM J. ELSOM, of Cortland, in the county of Cortland, in the State of New York, have invented new and useful Improvements in Fertilizer-Distributors, of which the following, taken in connection with the accompanying drawings, is a full, clear, and exact description.

This invention relates to the class of fertilizer-distributors in which the vehicle which carries the fertilizers is provided with a longitudinally-movable apron in the bottom of the vehicle-body for the purpose of moving the fertilizer to the distributing rear end of the body and which apron is subsequently reversed in its movement to return to its normal position for receiving another supply of fertilizer.

The chief object of this invention is to provide the machine with suitable means for automatically arresting the movement of the apron at its loading position in the body and at the end of its discharging position; and to that end the invention consists in the novel construction and combination of the component parts of the arresting mechanisms and auxiliary devices employed in connection therewith, as hereinafter described, and summed up in the annexed claims.

In the accompanying drawings, Figures 1 and 2 are elevations of opposite sides of a fertilizer-distributer embodying my invention. Fig. 3 is an enlarged view of the mechanisms which transmit motion to the apron, shown partly in section. Figs. 4 and 5 are longitudinal sections of the apron in its positions at the beginning and end of its rearward movement. Fig. 6 is a rear end elevation of the mechanisms for transmitting motion from the beater-shaft to the rear shaft of the chain-wheels which carry the apron. Fig. 7 is an enlarged plan view of the clutch mechanism which controls the movement of the apron, and Fig. 8 is a fragmentary face view of the gear-wheel which is adapted to transmit variable speed to one of the mechanisms which actuate the apron.

A denotes the body of the vehicle which carries the fertilizer to be distributed upon the field.

B is one of the rear traction-wheels of the vehicle.

C is the longitudinally-movable apron or

bottom of the body A, which apron is in the present case of a slightly greater length than the body A and has mounted on its front end the follow-board D. (Shown in Figs. 4 and 5 of the drawings.)

a represents one of the endless chains, to which are attached the transverse slats which form the apron.

b and b' are the wheels upon which the chain a is carried. The rear wheel b is fastened to the transverse shaft b², which I term the "apron-shaft," while the front wheel b' is mounted loosely on the shaft b³.

The apron C is required to travel back and forth to discharge the fertilizer at the rear end of the body A, as represented in Fig. 5, and then return to a position to serve as the bottom or floor of said body preparatory to loading the body with fertilizer, as shown in Fig. 4. To automatically arrest the movements of the apron at its arrivals at its extreme inner and outer position on the machine, I employ mechanisms which are actuated by the travel of the apron, as herein presently explained.

The forward movement of the apron C to a position to close the bottom of the body A, I derive from the shaft c of the beater F, which has a rapid rotary motion transmitted to it by means of a gear-wheel B', actuated by the traction-wheel B, preferably at the left-hand side of the machine, as shown in Fig. 2 of the drawings. The said gear-wheel meshes with a pinion B², which is fastened to or formed in integral with a sprocket-wheel B³, mounted on a stub-shaft c', projecting from a suitable bracket (not shown) attached to the side of the body A. A smaller sprocket-wheel B⁴ is attached to the beater-shaft c and connected with the sprocket-wheel B³ by a drive-chain c'.

At the right-hand side of the machine are two sprocket-wheels d d', mounted loosely on the shaft b and disposed a sufficient distance apart to admit between them a duplex clutch-collar e, which is mounted movably on the apron-shaft b and is provided internally with a longitudinal groove engaging a spline e³ on the shaft. The clutch-faces e' e² on opposite ends of the collar e are formed reverse to each other and adapted to engage one at a time the clutch members e⁴ and e⁵, formed on the sides of the sprocket-wheels d and d', respectively. A central position of the clutch-col-

lar *e* between the said clutch members prevents engagements of said parts, and thus the clutch-collar and apron-shaft remain at rest. At the same side of the machine the beater-shaft *c* has attached to it a gear-wheel *f*, and parallel with this shaft is a stub-shaft *c'*, on which is pivoted an eccentric *c''*. (Shown in Figs. 1 and 3.) Upon the hub of this eccentric is revolubly mounted a gear *c''*, to the side of which is rigidly secured a sprocket-wheel *c'*, connected by drive-chain *c''* with the sprocket-wheel *d* on the apron-shaft *b*, as shown in Fig. 6. By turning the eccentric *c''* the wheel *c''* is thrown in and out of gear with the wheel *f*, and thus the motion of the sprocket-wheel *d* is controlled. The said turning of the eccentric is effected automatically, as hereinafter described.

For imparting rearward movement to the apron *C*, I preferably employ mechanisms similar to those shown in the Letters Patent No. 789,498, dated May 9, 1905, which consist of the disk or annular plate *O*, mounted on the axle *T* of the rear traction-wheels *B* and rotating with said wheels. The innerface of the said disk has projecting from it concentric rows of teeth *t*, which rows are arranged with blank annular spaces *t'* between them, as shown in Fig. 8 of the drawings. Radially across the toothed side of the disk *O* is a shaft *g*, which is pivoted at opposite ends in bearings secured to a bracket *I*, firmly attached to the side of the body *A*.

On the shaft *g* is mounted a pinion *i*, which is movable lengthwise thereof and is provided in its hub with a longitudinal groove which engages a spline on the shaft. By sliding the said pinion toward and from the axis of the disk *O* it is caused to engage different rows of teeth *t*, and thus vary the speed of rotation of the pinion. This shifting of the pinion is effected by means of a hand-lever *J*, pivoted to the front portion of the body *A* and connected by a rod *i'* to one of the arms of a bell-crank *i''*, whose other arm is bifurcated and connected to trunnions on a ring *j*, seated loosely in a groove in the hub of the pinion *i*, as shown in Figs. 1 and 3 of the drawings.

To the outer end of the shaft *g* is fastened a worm *g'*, which engages a gear *g''*, mounted on a stub-shaft *g''*, projecting from the bracket *I*. To the side of the gear *g''* is fastened a sprocket-wheel *g''*, which by a sprocket-chain *g''* is connected to the sprocket-wheel *d'* on the end of the shaft *b*. This sprocket-wheel is thus revolved reverse from the sprocket-wheel *d* on the said shaft. When the clutch-collar *e* is in engagement with the clutch-member *e'* on the wheel *d*, the shaft *b* is turned in a direction which causes the apron *C* to travel forward, which movement is derived from beater-shaft *c* by the mechanisms hereinbefore described, and thus the apron *C* is moved at a considerable speed to position to

close the bottom of the body *A*. By then shifting the clutch-collar *e* to its neutral position the apron is left in said position.

The shifting of the clutch-collar *e* to its neutral position is effected automatically by the movement of the apron *C* through the instrumentality of two trip-levers *k* and *k'*, pivoted to the body *A* respectively at *l* and *l'*, as shown in Figs. 1, 4, and 5. The trip-lever *k* is located at the front of the body and extended upward from its fulcrum to render it conveniently accessible for the operator or driver of the machine to restore said lever and its coöperating lever *k'* to their required position for being actuated by the traveling apron. The trip-levers *k* and *k'* are connected to each other by means of a rod *l''*, so as to operate in unison. At a suitable distance from the rear end of the machine is a rock-shaft *m*, mounted in bearings on the body *A*, as shown in Fig. 7 of the drawings. To this shaft is attached an arm *m'*, which is connected by a rod *m''* to the trip-lever *k'*. To the outer end of the rock-shaft *m* is rigidly attached a collar *n*, which is provided with a fixed crank *n'* and with a circumferential groove *n''*, which extends obliquely around the collar. The said crank is connected by a rod *o* to an arm *o'*, which projects laterally from the eccentric *c''*.

A lever *p* is fulcrumed at or near the center of its length on a bracket *p'*, which is rigidly secured to the body *A*. Each end of said lever is bifurcated and provided on the inner sides of the prongs with lugs *r r'*, as indicated by dotted lines in Fig. 7. The lugs of one end of the lever *p* engage the groove *n''* in the collar *n*, while the lugs of the opposite end of the lever engage a circumferential groove *p''* in the clutch-collar *e*.

The operation of the machine is as follows: The apron *C* being in position to form the bottom of the body *A*, as shown in Fig. 4, and loaded with the fertilizer, the operator moves the lever *J* into a position which throws the pinion *i* out of engagement with the teeth *t* of the disk *O*, and thus leaves the apron *C* dormant in the aforesaid position during the time of taking the machine to the field designed to receive the fertilizer. The beater *F* is also retained at rest during said time by the operator setting the lever *L* into a position which throws the gear-wheel *B'* out of engagement with the traction-wheel *B* by means of suitable clutch mechanism actuated by a rod *s*, connected to the lever *L*. (Shown in Fig. 2.) The said clutch mechanism may be of any suitable and well-known construction. When the apron *C* is in the aforesaid position, the bracket *u*, which supports the follow-board *D*, presses on the end of an arm *u'*, attached to the trip-lever *k*, above the fulcrum thereof, as shown in Fig. 4. Said pressure throws the lever *k* to a position which causes the lower end thereof to push the trip-lever *k'* into a

What I claim as my invention is—

1. The combination, with the traction-wheel, beater-shaft and the reciprocating apron, of mechanisms actuated by the beater-shaft and propelling the apron in a forward direction, mechanisms actuated by the traction-wheel and moving the apron in a rearward direction, and tripping devices actuated by the traveling apron and controlling the aforesaid mechanisms. 75

2. The combination with the traction-wheel, apron-shaft and beater-shaft, of mechanisms actuated by the beater-shaft and rotating the apron-shaft in one direction, mechanisms actuated by the traction-wheel and rotating the apron-shaft in the opposite direction, trip-levers connected to each other to move simultaneously and actuated by contact with the ends of the traveling apron at the limits of its travels, means actuated by the trip-levers and depriving the apron-shaft of transmission of motion from the aforesaid mechanisms, and a lever affixed to one of the trip-levers for restoring the trip-levers to their operative position and disposed to be operated by the attendant of the machine. 85

3. The combination, with the body, the reciprocating apron, and mechanisms transmitting motion to said apron, of clutch mechanisms for operating the transmitting mechanisms alternately, tripping devices disposed to be actuated by the traveling apron to limit the movements thereof, a rock-shaft mounted in bearings on the body, means for transmitting motion from the tripping devices to the rock-shaft, a diagonally-grooved collar attached to the rock-shaft, and a lever engaging the groove of said collar and actuated thereby to shift the clutch mechanisms 95 as set forth. 100

4. The combination with the traction-wheel, apron-shaft and beater-shaft, of a gear attached to the beater-shaft, a pinion supported movably to and from engagement with said gear, mechanism transmitting motion from said pinion to the apron-shaft in one direction, mechanism transmitting motion from the traction-wheel to the apron-shaft in the opposite direction, tripping devices actuated alternately by the apron at the extremes of its travels, one of the actions of the tripping devices throwing the aforesaid pinion out of engagement, and the other action of the tripping devices depriving the apron-shaft of motion from the traction-wheel, and means disposed to be actuated by the operator and restoring the transmitting mechanisms to operative position. 115

5. The combination, with the reciprocating apron, traction-wheel and beater-shaft of mechanism transmitting motion from the traction-wheel to the apron in one direction, mechanism transmitting motion from the beater-shaft to the apron in the opposite di- 125

rearwardly-inclined position by means of the rod l and at the same time causes the rod m^2 to push the arm m' rearward sufficiently to carry the lugs r of the front end of the lever p midway in the diagonal groove n^2 of the collar n , and thus cause the opposite end of the lever p to hold the clutch-collar e out of engagement with both clutch members e^4 and e^5 . In this condition the said clutch-collar is retained while the machine loaded with fertilizer is conveyed to the field in which the fertilizer is to be distributed. Upon its arrival thereat the operator sets the levers J and L in positions to transmit motions from the disk O to the loosely-mounted sprocket-wheel d' and from the traction-wheel B on the opposite side of the machine to the beater-shaft and thence to the loosely-mounted sprocket-wheel d . Then the operator presses by his foot the upper end of the trip-lever k farther forward from where it was left by the pressure applied to the arm u' by the bracket u . The said further thrust of the lever k throws the clutch-collar e into engagement with the clutch member e^5 on the sprocket-wheel d' , and thus causes said wheel to impart motion to the shaft b , which moves the apron C rearward to discharge the fertilizer through the rear end of the body A . In said movement of the apron it becomes inverted at said end of the body, and the inverted portion is carried forward beneath the body A , where the front end of said inverted apron comes in contact with the trip-lever k' , as shown in Fig. 5, and pushes the same into a forwardly-inclined position at the time when the entire load of fertilizer has been discharged from the body A . The said movement of the trip-lever k' tilts the arm m' forward by means of the rod m^2 . This tilting of said arms turns the collar n so as to cause it to push the lever p into a position which throws the clutch-collar e out of engagement with the clutch member e^5 and into its neutral position, and thus arrests the motion of the apron. The operator then, by means of the trip-lever k , moves the rod m^2 to turn the collar n so as to cause the lever p to throw the clutch e into engagement with the wheel d , which receives a comparatively rapid motion from the beater-shaft and returns the apron C to its original position in the body A . In arriving at said position the apron is again arrested by the hereinbefore-described action of the trip-lever k , which again shifts the clutch-collar e so as to release both clutch members of the sprocket-wheels d and d' . Simultaneously with this action the crank n' on the grooved collar n turns the eccentric c^2 sufficiently to throw the pinion c^3 out of engagement with the gear f on the beater-shaft c . The machine is then ready to be started with another load of fertilizer to the field upon which it is to be distributed. 130

- rection, clutch mechanisms controlling said transmitting mechanisms, a lever pivotally supported on the vehicle-body and adapted to shift the clutch mechanisms, trip-levers 5 pivoted to the body and actuated by the travel of the apron, and rods connected to said levers and actuating the shifting-lever.
6. The combination with the body, apron-shaft and beater-shaft, a gear fastened to the beater-shaft, a stub-shaft secured to the body, an eccentric pivoted to said stub-shaft, a gear mounted revolubly on the eccentric, a sprocket-wheel rigidly attached to the side of the last-mentioned gear, a sprocket-wheel 10 mounted loosely on the apron-shaft and connected by chain to the first-mentioned sprocket-wheel, means for transmitting motion from the sprocket-wheel of the apron-shaft to the said shaft, trip-levers actuated 15 by the apron to limit the movements thereof, and means actuated by the trip-levers and turning the aforesaid eccentric and thereby throwing the adjacent gear in and out of engagement with the gear on the beater-shaft 20
- 25 as set forth.
7. The combination with the traction-wheels and apron-shaft, of wheels mounted loosely on the apron-shaft, mechanisms transmitting motion to said loosely-mounted 30 wheels in opposite directions from each other, a clutch sliding on the apron-shaft between said wheels and splined on the shaft, trip-levers disposed to be actuated by contact with the ends of the traveling apron at the limits 35 of its movements, means actuated by said trip-levers and moving the clutch out of engagement with both loosely-mounted wheels, and a lever disposed to be operated by the attendant of the machine and restoring the 40 trip-levers to their operative position and simultaneously throwing the clutch into engagement with one of the loosely-mounted wheels.
8. The combination with the apron-shaft 45 and beater-shaft, of a sprocket-wheel mounted loosely on the apron-shaft and having a clutch member fastened to it, a gear-wheel attached to the beater-shaft, a stub-shaft parallel with the beater-shaft, an eccentric 50 pivoted on said stub-shaft and provided with
- a laterally-projecting arm, a pinion mounted loosely on the eccentric and engaging the gear on the beater-shaft, a sprocket-wheel fastened to said pinion and connected by a sprocket-chain to the sprocket-wheel on the apron-shaft, a clutch-collar mounted movably on said apron-shaft and engaging a spline, a rock-shaft provided with an arm and with an obliquely-grooved collar formed with a crank, a rod connecting said crank 60 with the arm of the aforesaid eccentric, a lever engaging the collar and throwing the clutch-collar in and out of engagement, trip-levers actuated by the travel of the apron, and a rod connecting said trip-levers with the 65 arm of the rock-shaft as set forth.
9. The combination with the traction-wheel, apron-shaft and beater-shaft, two sprocket-wheels mounted loosely on the apron-shaft and provided with reverse-shaped clutch members on their adjacent sides, a gear-wheel attached to the beater-shaft, a stub-shaft parallel with the beater-shaft, an eccentric pivoted on said stub-shaft and provided with a laterally-projecting arm, 70 a pinion mounted loosely on said eccentric and engaging the gear on the beater-shaft, a sprocket-wheel fastened to said pinion and connected by chain to one of the sprocket-wheels on the apron-shaft, a clutch-collar 75 mounted movably on the apron-shaft between the two sprocket-wheels thereof and engaging a spline on the shaft, mechanisms transmitting motion from the traction-wheel to the other sprocket-wheel on the apron-shaft, a rock-shaft provided with an arm and an obliquely-grooved collar formed with a crank, a rod connecting said crank with the arm of the aforesaid eccentric, a lever actuated by the grooved collar to throw the 80 clutch-collar in and out of engagement, trip-levers actuated by the travel of the apron, and a rod connecting said trip-levers with the 85 arm of the rock-shaft substantially as set forth.
